UNITED STATES PATENT OFFICE.

LYMAN L. McCREA AND ROBERT V. COON, OF TROY, NEW YORK.

IMPROVEMENT IN GUARDS FOR RAILROAD-CROSSINGS.

Specification forming part of Letters Patent No. 175,368, dated March 28, 1876; application filed February 14, 1876.

To all whom it may concern:

Be it known that we, LYMAN L. McCREA and ROBERT V. COON, of Troy, in the county of Rensselaer and State of New York, have invented a new and useful Improvement in Flange Guards for Railroad-Crossings, of which the following is a specification:

Figure 1 is a top view of a portion of a railroad-track at a crossing, illustrating our invention. Fig. 2 is a cross-section of the same taken through the line $x x$, Fig. 1.

Similar letters of reference indicate corresponding parts.

The invention relates to certain improvements in a device for preventing horses' feet from getting caught upon the spike-heads, or between the rails and planking, at railroad-crossings.

The invention consists in the guard having one edge formed to fit upon the flange and into the neck of the rail, and its other edge formed to fit against the edge of the planking, concaved upon its upper side, and provided with a flange and lugs to underlap the planking and the flange of the rail between the ties, as hereinafter fully described.

A represents the ties, to which the rails B are spiked in the usual way. C is the planking, which is also spiked to the ties A. D is the guard, one edge, d^1 , of which is so formed as to fit upon the flange and against the neck of the rail, and the upper side of which is concaved, so as to be out of the way of the flanges of the car-wheels. The other edge d^2 of the guard is straight, and of a height equal to

the thickness of the planking, so that its top may be flush with the upper surface of said planking. The concavity in the upper side of the guard D inclines or curves from its bottom to the top of the edge d^2 , so that the opening between the said edge d^2 and the head of the rail B may be wider at its upper part than at its lower part, so that nothing can get caught in or wedged into said space. Upon the lower part of the edge d^2 of the guard D is formed a flange, d^3 , which underlaps the planking C, as shown in Fig. 2, and upon the lower part of the edge d^1 of said guard D are formed lugs d^4 , which underlap the flange of the rail B between the ties A, so that the guard D will be kept in place by the said ties, rail, and planking, without being spiked.

Having thus described our invention, we claim as new and desire to secure by Letters Patent—

The guard D, having one edge, d^1 , formed to fit upon the flange and into the neck of the rail B, and its other edge formed to fit against the edge of the planking C, concaved upon its upper side, and provided with a flange, d^3 , and lugs d^4 , to underlap the planking C, and the flange of the rail B between the ties A, substantially as herein shown and described.

LYMAN L. McCREA.
ROBERT V. COON.
